Primary Examiner — Ruth McInroy*(74) Attorney, Agent, or Firm* — Knobbe Martens Olson & Bear LLP(57) **CLAIM**

I claim the ornamental design for a barbecue hot plate assembly, as shown and described.

DESCRIPTION

FIG. 1 is a top, front, and right side perspective view of a barbecue hot plate assembly showing my new design; FIG. 2 is a bottom perspective view thereof;

FIG. 3 is a top view thereof;

FIG. 4 is a rear view thereof;

FIG. 5 is a front view thereof;

FIG. 6 is a right side view thereof; and,

FIG. 7 is a left side view thereof.
